UNITED STATES PATENT OFFICE

132,180

DESIGN FOR A BOTTLE OR SIMILAR ARTICLE

Meredith Stewart Ireys, Lancaster, Pa., assignor to Armstrong Cork Company, Lancaster, Pa., a corporation of Pennsylvania

Application December 17, 1941, Serial No. 104,682

Term of patent 14 years

To all whom it may concern:

Be it known that I, Meredith Stewart Ireys, a citizen of the United States, residing in Lancaster, county of Lancaster, and Commonwealth of Pennsylvania, have invented a new, original, and ornamental Design for a Bottle or Similar Article, of which the following is a specification, reference being had to the accompanying drawing, forming a part hereof, and in which the figure is an isometric view of a bottle or similar article showing my new design.

The bottle is square in cross section and the two side faces not shown are the same as those appearing in the figure.

The characteristic features of my design reside in the portions shown in full lines.

I claim:

The ornamental design for a bottle or similar article substantially as shown and described.

MEREDITH STEWART IREYS.
